US00D843267S

(12) **United States Design Patent** (10) **Patent No.:** **US D843,267 S**
(45) **Date of Patent:** **** Mar. 19, 2019**

(54) **UNMANNED AERIAL VEHICLE**

(71) Applicant: **Shenzhen HighGreat Innovation Technology Development Co., Ltd.**,
Shenzhen, Guangdong (CN)

(72) Inventor: **Jianmin Gao**, Guangdong (CN)

(73) Assignee: **Shenzhen HighGreat Innovation Technology Development Co., Ltd.**,
Shenzhen (CN)

(**) Term: **15 Years**

(21) Appl. No.: **29/636,554**

(22) Filed: **Feb. 9, 2018**

(30) **Foreign Application Priority Data**

Oct. 11, 2017 (CN) 2017 3 0482452

(51) **LOC (11) Cl.** **12-01**

(52) **U.S. Cl.**

USPC **D12/16.1**

(58) **Field of Classification Search**

Primary Examiner — Marissa J Cash

(57) **CLAIM**

The ornamental design for an unmanned aerial vehicle, as shown and described.

DESCRIPTION

FIG. 1 is a front elevational view of an unmanned aerial vehicle showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a top, front and right side perspective view thereof;

FIG. 8 is a top, rear and right side perspective view thereof;

FIG. 9 is a top, front and right side perspective view showing the unmanned aerial vehicle in a folded state; and,

FIG. 10 is a rear perspective view showing the unmanned aerial vehicle in a folded state.

The broken lines in the drawings illustrate portions of the unmanned aerial vehicle which form no part of the claimed design.

1 Claim, 10 Drawing Sheets
